UNITED STATES PATENT OFFICE.

WILLIAM A. RINGLER, OF PHILADELPHIA, PENNSYLVANIA, ASSIGNOR TO THE GLOBE-WERNICKE CO., A CORPORATION OF OHIO.

VISIBLE INDEX.

Application filed November 18, 1924. Serial No. 749,625.

This invention relates to index devices, and particularly to the type commonly known as visible indexes, in which a series of index cards are supported in a frame with the free edges of the cards projecting one beyond the other to leave a narrow margin of the surface of each card exposed, upon which exposed portion any suitable indexing or identifying characters, such as names, addresses, numbers, etc., may be placed so as to be always visible.

An object of this invention is to provide an improved index device in which one or a plurality of index elements may be supported upon one carrier with all of the elements movable to expose both faces; with which increased spacing at the exposed marginal edges may be provided in a simple manner at any time, for any index element; with which any of the index elements of a group may be laterally offset relatively to the others in order to distinguish them by their offset position; with which removable signals may be utilized in a simple manner and of various sizes; with which the various index elements will remain either flat or raised selectively; with which interlocking of the index units to prevent telescoping may be accomplished in a simple and effective manner; and with which the index elements may be applied to or removed from their carriers in a simple manner without danger of confusion.

A further object is to provide an improved index device which will accomplish any or all of the above objects and which may be made from stamped sheet material; and which will be convenient, light in weight, compact, durable, and relatively inexpensive. A further object is to provide an improved follower block having simple, effective and convenient means for securing it in various adjusted positions; and which will be relatively inexpensive.

Various other objects and advantages will be apparent from the following description of an embodiment of the invention, and the novel features will be particularly pointed out hereinafter in connection with the appended claims.

The invention comprises the various details and features which will be more partic-

ularly referred to as the description of an embodiment of the invention proceeds.

In the accompanying drawings:

Fig. 1 is an elevation of a portion of an index device constructed in accordance with this invention, with certain portions broken away to better show parts beneath;

Fig. 2 is a longitudinal sectional elevation of the same;

Fig. 3 is an elevation of one of the carrier strips of the same;

Fig. 4 is an end elevation of the same;

Fig. 5 is an elevation of one of the index units detached from the frame;

Fig. 6 is a sectional plan of the same with the section taken substantially along the line 6—6 of Fig. 5;

Fig. 7 is an end elevation of the same;

Fig. 8 is a transverse sectional elevation of the same, the section being taken substantially along the line 8—8 of Fig. 5;

Fig. 9 is an elevation of one of the index elements detached from its carrier;

Fig. 10 is a sectional elevation through an index unit, having two index elements mounted upon a single carrier;

Fig. 11 is a longitudinal sectional elevation of a portion of the index device, showing the use of the spring tongues of the index element as resilient props to hold an element in upright position;

Fig. 12 is an elevation of an index unit having a special spacer strip attached thereto for increasing the marginal portion of that unit which will be exposed;

Fig. 13 is an elevation of several units assembled together, with a special spacer on one of the units to illustrate the double spacing;

Fig. 14 is a plan of one of the blanks from which the special target or signal tabs are torn; and

Fig. 15 is a side elevation of a carrier with a plurality of elements mounted thereon to increase its capacity.

Referring particularly to Figs. 3 to 5, inclusive, the particular carrier or holder for index elements which is illustrated, comprises an elongated strip 1, stamped of the desired length and width from suitable flexible sheet material, such as metal, fibre, or heavy paper or cardboard, preferably the

paper or cardboard. Both ends of the strip are bifurcated by central notches or slots 2, which slots or notches provide integral end tongues or arms 3 of equal width. By reason of the flexible sheet material of which the strips are made, they may be flexed laterally so as to enable them to be removed from or inserted in opposing guides or channels α of an index frame b , as will be explained more fully hereinafter.

A plurality of index elements 4 (see Fig. 9 particularly) are formed of suitable material, such as paper or cardboard, being stamped of the desired size and each provided adjacent its side margins with apertures 5 of a diameter sufficiently large to receive the arms or tongues 3 of the carrier strip 1. The tongues 3 may be inserted through the apertures 5 by first flexing the carrier strip 1 until the ends of the tongues on opposite ends are brought together sufficiently to pass the two lower tongues respectively into or through the apertures at opposite sides of the element, whereupon, if the strip is released, it will, in straightening out, pass the arms or tongues 3, further through the apertures and assume the position shown in Fig. 5. It is also possible to apply the index element to the strip by first passing one of the tongues through an aperture along one side of the element and then flexing the strip to enable a tongue at the other end of the strip to be passed through an aperture at the other side of the element.

Each index element 4 is provided with two rows of transversely extending perforations or scorings 6 and 7 upon opposite sides of an imaginary line joining the centers of the apertures 5 so as to facilitate the bending or flexure of the index element in a transverse direction. The line of perforations 6 facilitates the bending of the marginal portion 8 of the element back upon itself (as shown particularly in Figs. 5, 7 and 8) to cooperate with an adjacent carrier strip in effecting the desired spacing between the index elements. The other line of perforations or scorings 7 facilitates flexure of the index elements, thus permitting swinging of each element upon a scored or perforated line as a hinge to expose the under face. Preferably, the line 7 consists of scorings adjacent the edges as designated at 9 and a central portion composed at its ends of scorings and at its intermediate portion of a row of perforations 10.

The body of the index element is also cut along the lines 11, 12 and 13, (see Figs. 5 and 9) at points adjacent opposite margins of the index element, the lines 11 and 13 extending toward the carrier strip from the line 7 and the line 12 connecting the projecting ends of the adjacent lines 11 and 13, thus forming tongues 14 cut out from the

interior or body of the index element and extending toward the carrier strip. When an index element is swung upwardly as shown in Fig. 11, in order to expose the under face thereof, the tongues 14 will swing with the body of the element and by engagement with the carrier with which it overlaps, will act as resilient prop members which will hold the index element in its upper or forward position. At the same time, when force is applied, such tongues will flex and yield to permit return of the elements to their overlapping condition.

When the carrier strips 1 with the attached index elements 4 are assembled between the opposite guides α of the frame b as shown in Fig. 1, the turned-over margins 8 will hook over the upper edge of the next lower carrier strip and limit the telescoping of the carrier strips and elements (see Fig. 11). This causes a progressive overlapping of the index elements with a marginal portion of the face of each index element exposed.

It is frequently desirable to offset one or more of the index elements laterally relatively to the other elements, so that by reason of the emphasis placed upon such offset elements, they may be readily located without special search. To accomplish this result, the slots or notches 2 are preferably made of sufficient length, and the carrier strips made sufficiently longer than the width of the index elements, to permit of the lateral shifting of the index elements upon the strips. This offsetting of the index elements is illustrated in Fig. 1 wherein the index element designated by the character c is offset. It will be understood that this offsetting may be readily changed at any time by merely shifting any of the index elements into and out of offset positions.

In order to obtain increased spacing between any of the index elements, special spacing elements or strips 15 may be employed. These spacing strips consist of strips of sheet material having apertures 16 spaced apart lengthwise a distance corresponding to the distance between the apertures 5 of the index elements, so that either the used or unused tongues or arms 3 of any carrier may be passed through the apertures 16 of a spacer strip, and mount it as shown in Figs. 12 and 13, in which the unused or upper tongues 3 are shown as thus employed. One of the longer marginal edges of the spacer strip is spaced from the apertures 16 a distance sufficient, when the spacer strip is mounted upon a carrier with this marginal edge projecting above the carrier, to effect the desired wider spacing between the element attached to the same carrier and the element attached to the carrier immediately above. The projecting edge of the spacer strip interlocks between the turned-

over marginal portion 8 and the lower portion of the carrier strip of the element immediately above the same, as well as with the adjacent portion of this upper element 5 in the same manner that the upper edge of each carrier strip interlocks with a marginal portion 8 when the special spacer strip is dispensed with. By variations in the widths of the spacer strips 15, it will thus be observed 10 that selected variations in the spacing between index elements may be obtained.

It is frequently desirable to especially distinguish certain index elements for short intervals only, and to avoid the necessity 15 of placing permanent markings upon such index elements, separable or detachable targets or tabs have been provided, which will be visible at the free or exposed 20 marginal edges of the index elements when the latter are in their normal position. This idea has been disclosed and claimed broadly in my prior United States Patent 25 #1,480,419, issued January 8th, 1924. In that case the signal tab consisted of an elongated piece of flexible sheet material having 30 a folded-over end which was hooked over the upper end of an index element and confined thereon by the pressure of the index 35 element next above. This method of attaching the signal tabs was open to the disadvantage that when for any reason the index elements were separated slightly in order to remove or insert one the signal 40 tabs were released and frequently fell out or became detached from position and could not be replaced without searching a special record to ascertain to which index element they should be attached.

40 In the present invention, each signal target, strip, or tab *d*, *e*, *f*, etc. is hooked over the folded upper edge of the related index element, beneath the carrier strip thereof, as shown in Fig. 1, so that it will 45 be held or interlocked thereon between the carrier strip and the index element. With such a mounting, the signal target or tab will remain attached to the index element even though the latter with its carrier is 50 removed and carried about, and there is little danger that it will become unintentionally removed or detached from the index element to which it relates. Such a tab or 55 target may be adjusted laterally upon the index element to various display positions, and may be made of different colors as explained in the prior patent referred to.

It is also frequently the case that the 60 small strips usually employed for this purpose do not provide sufficient space upon which to place special information or characters which one does not desire to have entered upon the index element as a permanent part of the record. Accordingly, 65 with the present invention, the signal

strips, targets, or tabs are formed in multiple in a single blank or sheet 17, such as shown in Fig. 14, the sheet or blank 17 being provided with spaced lines or perforations 18 which facilitate separation of 70 the sheet or blank into the sections *d*, *e*, *f*, each section corresponding in size to the area between the perforated lines. The sheet or blank is also provided with a row of perforations or scorings 19 which extends transversely of the perforated lines 18, so as to facilitate the folding of the ends 75 of the signal strips or tabs to provide the hooks by which they may be attached to the index elements.

The sheet or blank is also preferably provided with another line of perforations 20 which extends transversely of the perforated lines 18. By reason of the perforated line 20 whenever a signal target or tab of 80 a plurality of sections is detached, one may detach the extra tip ends 21 so that but a single attention attracting end will be exposed on the visible marginal edge of the index element. In this manner any desired 85 area on the signal strip or tab may be provided for carrying all of the desired information for temporary use, and at the same time only a sufficient portion of the tab will be visible along the exposed or visible marginal edge of the index element to direct 90 attention thereto without covering the identification information already provided upon the exposed marginal portion of that 95 index element.

100 Each index element 4 and its carrier strip 1 together form what may be termed an index unit, and these index units are assembled together in interlocking relation in an index frame as shown in Fig. 1 and explained hereinbefore. In order to prevent separation of the index units a suitable follower block may be employed, and for this particular purpose I have found the follower block illustrated in Figs. 1 and 2 to 105 be especially valuable. This follower block comprises a sheet 22 of bendable material, such as heavy paper or cardboard, folded at 23 to form two flaps 24 and 25. The two flaps may be secured together adjacent their 110 line of connection or the line of fold by suitable means, such as by rivets or staples 26.

115 This follower block thus provided has marginal tongues or extensions 27 upon 120 opposite side edges and adjacent the line of fold, these tongues serving as guides which extend into the usual guide grooves *a* of the supporting frame *b*. The under flap 25 passes beneath the uppermost carrier strip, 125 and the upper flap 24 passes over the same so as to hold the upper carrier strip against the others and prevent its displacement upwardly. In order that access may be had conveniently to the index elements 130

covered by the upper flap 24, the latter is provided with one or more lines of perforations or scorings 27^a extending from side to side, or the flap is otherwise weakened so that it will bend freely upwardly and expose the index elements beneath it.

In order to lock the follower block in any adjusted position along the frame, a wedge strip 28 is provided of a length approximately equal to the distance between the outer ends of the opposite tongues or guide extensions 27, but preferably approximately equal to or slightly greater than the distance between the bottoms of the opposite guide grooves of the frame in which it slides. This wedge strip is pivoted intermediate its ends to the upper edge of the follower block by suitable means, such as by a metal eyelet 29. The wedge strip 28 is thus rotatable about the axis of the eyelet rivet 29 and when rotated into a position in which it extends between the guides of the frame the ends will enter the guides beneath the guide tongues 27 and wedge the same against the sides of the guide grooves with sufficient friction to prevent unintentional displacement of the follower block along the frame. When the length of the wedge strip is slightly longer than the distance between the bottoms of opposite guide grooves of the frame, the ends will wedge against the bottoms of the frame grooves, just before moving completely therein, and for this reason also hold the block against movement along the frame.

It will be observed that with this manner of mounting the index elements upon the carrier strips, a plurality of the index elements may be applied to any one carrier strip (as shown in Fig. 10) in order to increase the effective capacity of the particular index unit, and this capacity may be decreased by the removal of the extra index elements on the same carrier when they are no longer necessary. In case the extra index elements are utilized they may be slightly shorter in length from the lines of perforation or scoring 7 so that no matter how many of the extra elements are applied to a carrier the marginal portion carrying the identification characters will always be exposed so that the replacing of this information upon each added index element will be unnecessary. This construction is shown in Fig. 15, where a shorter extra element is designated by the reference character 4^a. If the extra index elements are of the same size as the regular elements, they may be placed beneath the regular elements when applied to a carrier so that they will not conceal the identification or index characters upon the exposed marginal edge of the regular index element. Also in such case the extra index elements may be placed at the front of the regular elements, upon the upper tongues

of the carriers, thereby to expose a lower margin of the regular elements.

It will be observed that by the use of the extra spacer strips, wider exposed marginal portions of any card or index element may be obtained at any time quickly and in an effective manner. This increased spacing is shown in Fig. 13. The special signal targets or tabs of any desired area may be applied to any index elements to carry temporary information and effectively indicate on the exposed margin the fact that such temporary information is there without covering the usual identification symbols upon the exposed margin of the index element, and such signal tabs will be attached to the index elements in such a manner that they will not become accidentally or unintentionally displaced in the normal use of the index device. Any number of the index elements may be emphasized or have attention directed to them by offsetting them laterally as explained. All of these elements will be held together in a simple manner by the follower block which is wedged in position by the wedge strip.

While it is preferable to have two tongues upon each end of the carrier strip, as illustrated, it will be understood that but a single tongue or arm at each end of the carrier strip may be utilized, and the spacer strip applied to the same arms or tongues as the index elements. It will also be understood that while the carrier is preferably formed of flexible sheet material in order that any unit may be removed from the frame by merely flexing the carrier strip without disturbing the other units, and in order that the carrier strip may be more readily attached to or removed from an index element, the invention also contemplates the use of relatively rigid carrier strips in which case the lengths of the slots or arms upon the ends of the carrier strips are sufficient to permit of a sliding of the index elements upon the arms until either edge of the index element is removed from an end of the carrier strip, whereupon by a reverse sliding movement the other edge may be disengaged from the other end of the carrier. The index element may be reapplied by reversal of these movements. Where a rigid carrier is used, such carriers must be inserted or removed from the frame by first placing them in a somewhat diagonal position to permit the ends to pass beneath the guide flanges of the supporting frame.

It will be understood that various changes in the details, materials and arrangement of parts, herein described and illustrated for the purpose of explaining the nature of the invention, may be made by those skilled in the art, within the principle and scope of the invention as expressed in the appended claims.

I claim:

1. In an index device, a carrier for index elements formed of a strip of sheet material having end portions serving as guides, and 5 also having integral aligned tongues at the end portions extending in an outward direction upon which one or more index elements may be mounted.
2. In an index device, a carrier for index 10 elements formed of a flexible strip of sheet material, having integral tongues at the end portions extending outwardly, and an index element mounted upon said tongues.
3. In a visible index device, an index unit 15 comprising a carrier having oppositely extending tongues spaced apart lengthwise of the carrier, and an index element having apertures spaced apart a distance approximately corresponding to the spacing between 20 the base portions of the tongues, the tongues extending through the apertures so as to detachably mount the index elements thereon.
4. In a visible index device, an index unit 25 comprising a carrier flexible in a transverse direction and having oppositely extending tongues spaced apart lengthwise of the carrier, and an index element having apertures spaced apart a distance approximately corresponding to the spacing between the base 30 portions of the tongues, the tongues extending through the apertures so as to detachably mount the index elements thereon.
5. In an index device, an index unit comprising a flat carrier, an index element se- 35 cured to said carrier intermediate its margins so that it will extend in both directions transversely of the line of attachment to the carrier, the portion of the element ex- 40 tending beyond the line of attachment on one side being folded back upon itself to form spacing means when hooked over an adjacent unit.
6. In a visible index device, an index element having apertures adjacent opposite 45 margins by which the element may be mounted; the element also having rows of perforations upon opposite sides of and parallel to an imaginary line joining the centers of the apertures so that said rows 50 of perforations will facilitate bending and flexing of the element.
7. In a visible index device, a carrier for index elements having spaced tongues and an index element having apertures through 55 which the tongues pass, said tongues having lengths permitting lateral sliding adjust- 60 ment of the index elements thereon without disengagement therefrom, whereby any of the elements may be laterally offset from the others to direct attention thereto.
8. In a visible index device, a carrier for index elements comprising a flexible strip of sheet-material having tongues extending in a direction lengthwise thereof, and an 65 index element having apertures through
- which the tongues pass, the tongues having lengths which will permit of considerable lateral adjustment of the index element thereon without becoming disengaged from the element, whereby any element may be 70 adjusted laterally to an offset position relatively to the other elements in a set, to direct attention thereto.
9. In a visible index device, a carrier for index elements comprising a strip of flexible 75 sheet-material having furcated ends, and an index element having spaced apertures adjacent its margins through which two of the arms below the uppermost arms of the furcations at opposite ends may be passed by flexing the carrier to contract the distance between the ends of the tongues, the furcations being continued lengthwise sufficiently to permit of considerable lateral adjustment of the index elements without detachment therefrom, whereby any element of the series may be laterally offset relatively to the others to indicate by such offset position any desired classification. 80
10. In a visible index device, a carrier for index elements having furcated ends, an index element having apertures through which arms of the furcated ends may extend to form means of attachment between the two, the portion of the element extending beneath the carrier and beyond the apertures being folded back upon itself to provide a spacing part. 85
11. In a visible index device, a carrier for index elements having bifurcated ends, an index element having apertures through which the lower arms of the bifurcated ends may extend to form means of attachment between the two while the upper portion of the carrier forms spacing means, the portion of the element extending beneath the carrier and beyond the apertures being folded back upon itself to provide a spacing part, and a spacing element comprising a strip of material having apertures through which the upper arms of the bifurcated ends may extend so as to increase the spacing through its effective upward widening of the carrier. 90
12. In a visible index device, an index unit comprising a carrier for index elements having tongues, an index element connected to said carrier by said tongues so as to extend beneath the same, and a target strip having a hooked end, hooked over the edge of the index element beneath the carrier, so as to be held in position upon the face of the index element between the carrier and the element. 95
13. In a visible index device, a target blank 125 comprising a sheet of flexible material perforated to form strips, the sheet being also perforated adjacent to and spaced from a margin in a direction transversely to the preceding perforations, whereby a target 130

member of any number of strips width may be torn from a sheet, and any of the tip ends removed by the transverse perforations to provide an indicating tab projection on the 5 member, having a width of one or more of the strips as desired.

14. In a visible index device, a follower block comprising a member having lateral guide extensions, and a locking strip pivoted to the member so as to be swung into 10 and out of a position in which an end extends at least coextensive with one of said lateral extensions to wedge the lateral extension in a guideway in which it may be 15 disposed.

15. In a visible index device, a follower block comprising a follower member having lateral tongues serving as guides, and a locking strip pivoted intermediate of its ends to 20 said member so as to be oscillatable thereon into and out of positions in which its ends are in superposed relation with the guide tongues so as to wedge the latter in guides in which they may be disposed.

25 16. In a visible index device, a follower block comprising a member having lateral tongues serving as guides, and a locking strip pivoted intermediate of its ends to said member for oscillation thereon into and out 30 of positions in which its ends extend beyond the outer ends of the tongues so as to engage the guideways in which the tongues are sliding before moving into complete alignment with the tongues.

35 17. In a visible index device, a carrier having its ends bifurcated to form arms of equal width on the ends, and an index element having apertures adjacent opposite side edges through which the lower arms on the opposite ends of the carrier may be passed to effect an attachment between the carrier and element.

45 18. In a visible index, the combination with a record sheet having a holding portion, a recording portion and spaced apertures, of a sheet-carrier comprising a strip of material bifurcated at its ends to form lower portions to enter said apertures and secure the sheet carrier to the record sheet.

50 19. In a visible index, a record sheet having a weakened portion dividing it into two portions, one by which it may be supported and the other for carrying information, said supporting portion having an opening at 55 each end thereof adapted to receive and be supported by the ends of a sheet carrier therefor.

60 20. The combination with a record sheet having a weakened line on which it is foldable to form a holding portion comprising a front flap and a rear flap, the front flap having an aperture at each end, of a sheet carrier comprising a strip of material having slotted ends to provide end portions 65 below the top thereof to enter said apertures

and extend between said front and rear flaps.

21. The herein described new article of manufacture, comprising a follower block having a body portion and end guiding portions, and a locking strip pivoted to said 70 body portion and adapted to be brought into registry with said end guiding portions.

22. In a visible index device, a carrier for index elements having relatively upper and lower tongues, an index element having 75 apertures through which the lower tongues may extend to form means of attachment between the two while the upper portion of the carrier forms spacing means, the portion of the element extending beneath the carrier 80 and beyond the apertures being folded back upon itself to provide a spacing part, and a cooperating spacing element comprising a strip of material having apertures through which the upper tongues may pass to increase the spacing through the effective widening of the carrier by the strip.

23. In a visible index device, a carrier for index elements having relatively upper and lower tongues, an index element having 90 apertures through which the lower tongues may extend to form means of attachment between the two while the upper portion of the carrier forms spacing means, the portion of the element extending beneath the carrier 95 and beyond the apertures being folded back upon itself to provide a spacing part, and a cooperating spacing element comprising a strip of flexible sheet material having apertures through which the upper tongues may pass to increase the spacing through the effective widening of the carrier by the strip.

100 24. In a visible index device, a carrier and spacer for index elements, an index element attached to said carrier, and a cooperating spacer element detachably connected to the carrier for increasing the spacing between the element mounted on that carrier and the next adjacent element.

110 25. In a visible index device, an index carrier and spacer having integral tongues, and a cooperating spacing part provided with apertures through which said tongues may be passed in order to support said part 115 detachably upon said carrier.

120 26. In a visible index device, a carrier for index elements having relatively upper and lower tongues, an index element having apertures through which the lower tongues may extend to form means of attachment between the two while the upper portion of the carrier forms spacing means, and a cooperating spacing element comprising a strip of material having apertures through which the upper tongues may pass to increase the spacing through the effective upward widening 125 of the carrier by said strip.

130 27. In a visible index device, a carrier for index elements comprising a strip of

- flexible sheet material having forked ends and an index element having apertures through which two opposite arms below the uppermost arms of the forked ends may pass when the carrier is flexed transversely. 5
28. In a visible index device, a carrier for index elements comprising a strip of flexible sheet material having forked ends, and an index element having apertures through 10 which two opposite arms below the uppermost arms of the forked ends may pass when the carrier is flexed transversely, the forked portion of the carrier extending lengthwise thereof sufficiently to permit of a limited 15 sliding movement of said element lengthwise of the carrier, whereby any element may be adjusted laterally to offset position relatively to the other elements in a set. 20
29. In an index device, a sheet carrier and spacer having a plurality of integral tongues adjacent each end, an index sheet having apertures adapted to receive a pair of said tongues below the uppermost so as to be supported thereby, and means adapted to engage a higher pair of said tongues so as to provide increased spacing between a plurality of said carriers and sheets with edges 25 of said sheets in overlapping relation. 30
30. In an index device, a sheet carrier having a plurality of integral tongues adjacent each end, an index sheet having apertures spaced apart to receive a pair of said tongues below the uppermost tongues respectively at opposite ends of the carrier so 35 as to be supported thereby, and a tongue formed on said sheet between said apertures and extending toward the sheet carrier for holding the recording portion of the index sheet in a position to expose its under face 40 which extends below the carrier. 31. In an index device, a flexible holder strip having a plurality of integral tongues adjacent each end thereof, a record sheet
- having apertures into which opposite tongues below the uppermost may be inserted when said strip is flexed transversely so that said inserted tongues support said record sheet, and means for engaging a plurality of said strips so as to support said sheets in a series with edges thereof in overlapping relation. 45
32. In an index device, frame means, a series of record sheets having apertures, a series of holder strips having integral tongues formed adjacent the ends thereof and adapted to detachably enter said apertures, said strips being detachably supported by said frame means with said strips in overlapping relation, and tongues on said record sheets adapted to engage adjacent underlying holder strips for holding the recording portions of the record sheets in a position to expose their under faces which extend below the holder strips, said tongues on the record sheets being independent of 50 said apertures 55
33. In a visible index device, a carrier for index elements having divided ends forming a plurality of arms, and an index element having spaced apertures through which two opposite arms on opposite ends below the uppermost arms may extend respectively to effect an attachment between the carrier and the element. 70
34. In a visible index device, a carrier for index elements comprising a strip of flexible sheet material having its ends divided to form a plurality of arms at each end, and an index element having spaced apertures through which two opposite arms at opposite ends below the uppermost arms may pass when the carrier is flexed transversely. 75

In witness whereof, I hereunto subscribe my signature.

WILLIAM A. RINGLER.
